UNITED STATES PATENT OFFICE.

BENJAMIN GROSS, OF NEW YORK, N. Y., ASSIGNOR TO BENJAMIN GROSS COMPANY, INC., OF NEW YORK, N. Y., A CORPORATION OF NEW YORK.

DESIGN FOR A JEWELRY-DISPLAY STAND.

Application filed February 23, 1924. Serial No. 8,718. Term of patent 3½ years.

To all whom it may concern:

Be it known that I, BENJAMIN GROSS, a citizen of the United States, residing at New York city, in the county and State of New York, have invented a new, original, and ornamental Design for a Jewelry-Display Stand, of which the following is a specification, reference being had to the accompanying drawing, forming part thereof.

The figure is a perspective view of a jewelry display stand showing my new design.

I claim:

The ornamental design for a jewelry display stand as shown.

BENJAMIN GROSS.
